UNITED STATES PATENT OFFICE.

WILLIAM BLOCK, OF CHICAGO, ILLINOIS.

DESIGN FOR A LAMP BASE.

Application filed October 15, 1925. Serial No. 15,133. Term of patent 3½ years.

To all whom it may concern:

Be it known that I, WILLIAM BLOCK, a citizen of the United States, residing at Chicago, in the county of Cook and State of Illinois, have invented a new, original, and ornamental Design for Lamp Bases, of which the following is a specification, reference being had to the accompanying drawing, forming part thereof.

of a base embodying my design, the balance of the ornamentation within the dotted outline being a repetition of the fragment shown; and

Figure 2 is a side elevational view of the same.

I claim:

The ornamental design for a lamp base as shown.

WILLIAM BLOCK.
